DESIGN FOR A DISH

Johann Martin Stangl, Flemington, N. J., assignor to Fulper Pottery Company, Trenton, N. J., a corporation of New Jersey

Application October 24, 1934, Serial No. 53,740

Term of patent 3½ years

To whom it may concern:

Be it known that I, Johann Martin Stangl, a citizen of the United States, residing at Flemington, in the county of Hunterdon, State of New Jersey, have invented a new, original, and ornamental Design for Dishes, of which the following is a specification; reference being had to the accompanying figures of the drawing, forming part thereof.

the design of the present invention, a portion only of the complete design being shown in detail it being understood that the ornamentation is continued throughout the dish, and

I claim:

The ornamental design for a dish as shown and described.

JOHANN MARTIN STANGL.
